DOOR CATCH

Frans O. Klingborg, San Mateo, Calif., assignor of
one-half to H. D. Currence, San Mateo, Calif.

Application March 6, 1940, Serial No. 322,429

3 Claims. (Cl. 16—142)

This invention relates to a door catch. More specifically, this invention relates to a door catch such as may be used in connection with the doors of cabinets and other articles of furniture 5 and in like instances wherein it is desirable to retain a door in closed position.

It is an object of this invention to provide a door catch of the class described which will effectively retain a door in closed position so long as 10 that is desired, but which will not interfere with the intentional opening of the same.

Another object of the invention is to provide a door catch of the class described which may be quickly installed; which will resist wear; which 15 has few working parts and which will require no manipulation in the opening or closing of the door in connection with which it is used.

I am aware of the fact that many devices have been devised for the specific purposes for which 20 this invention is intended, but it has been my observation from a careful study of the art, that the known devices are objectionable for many reasons. It has been my observation that the familiar spring ball and socket door catch is unsatisfactory because of its tendency to stick. 25 Frequently this is caused by a swelling or slight warping of the wood in the door, and in other instances, it is due to the fact that this specific catch is prone to get out of order. In some instances use has been made of door catches which are manually operable by the door knob, but these are costly and objectionable because they frequently get out of order.

In general terms, this invention consists in applying 30 a door catch means to the door hinges instead of placing it at the opposite vertical edge of the door. More specifically, my invention consists in applying a yieldable finger or catch to one flap of the hinge and arranging a slot 35 in the opposite hinge flap into which the said catch or finger is inserted in the door closing operation, the frictional engagement of the said catch or finger with the opposite flap serving to retain the door in its closed position.

45 In the drawing:

Fig. 1 is a perspective view of a door frame and door with hinges embodying the invention.

Fig. 2 is a front elevation of a hinge embodying the invention.

Fig. 3 is a top edge plan view of the hinge of Fig. 2.

Fig. 4 is a sectional view showing a hinge embodying the invention in its closed position, and 55 Fig. 5 is a fragmentary front elevation of a

hinge embodying a modification of the invention.

The numeral 10 designates a door frame or jamb set in a wall structure 11, there being a door 12 connected to the jamb by means of conventional hinges 13. Moreover, the door 12 is fitted with a common knob 14 (see dotted lines in Fig. 1) as a convenient means of opening and closing the same.

In the form illustrated in the drawing the 10 hinges consist in the customary flaps 15 and 16 interconnected by a pin 17.

In the hinge 13 I provide the opposed apertures 18 and 19, the same being punched in the flaps 15 and 16, respectively. A finger 20, of relatively stiff but yieldable material, such as spring metal or the like, and having one end bent at right angles as at 21 (see Fig. 3) for attachment to the obverse side of flap 16 in any accepted manner, such as by the rivet 22, projects through 20 the aperture 19 in flap 16. The yieldable finger 20 is adapted to enter the aperture 18 in the opposing flap 15 and by frictional engagement hold the flaps in closed relation (see Fig. 4).

To facilitate the engagement of flap 15 by 25 the yieldable finger 20, the free end of the latter is bent, as at 23.

While in Figs. 1 to 4 the apertures 18 and 19 and finger 20 are shown vertically disposed, the 30 device will operate with equal facility if arranged, as a matter of preference, on a horizontal plane (see Fig. 5).

In applying the hinge 13 fitted with the device 35 of my invention, the usual procedure of first cutting recesses in door edge and jamb for the hinge flaps is supplemental to the extent of cutting a recess 24 in the jamb 10, to receive the extreme end of the finger 20 (see Fig. 4).

It will be understood from the foregoing that 40 opening and closing of the door 12 is accomplished in the usual manner, i. e., by pulling and pushing on the knob 14. When the door is pushed inwardly the finger 20 enters the aperture 18 and snaps over one edge thereof to retain the door in closed position. When pull is exerted on the knob 14, the finger 20 will yield and be withdrawn from engagement with the flap 15.

It will be appreciated that this invention may take forms in addition to that illustrated herein without departing from the spirit thereof, hence I desire full protection in accordance with the scope of the appended claims.

The invention claimed is:

1. In a door catch, the combination of a door supporting hinge having opposed flaps, one of said flaps having an aperture therein, the other flap having a relatively stiff but yieldable finger thereon in substantial registry with the aperture in the first named flap and adapted to enter said aperture and frictionally engage one of the edges of the said flap defining the aperture there-
10 in when the flaps are closed together.
2. In a door catch, the combination of a door supporting hinge having opposed flaps, said flaps having apertures therein in registry, a relatively stiff but yieldable finger projecting through one
15 of said apertures and being adapted to enter the aperture in the opposite plate to frictionally en-

gage one of the edges of said flap defining the aperture therein when the flaps are closed together.

3. In a door catch, the combination of a door supporting hinge having opposed flaps, said flaps having apertures therein in registry, a relatively stiff but yieldable finger projecting through one of said apertures and being adapted to enter the aperture in the opposite flap to frictionally en-
10 gage one of the edges of said flap defining the aperture therein when the flaps are closed together, the opposite end of said finger being bent at right angles and attached to the obverse side of the flap through which it projects.
